J. P. NICOLLE,
CLEAT FOR BARRELS,
APPLICATION FILED AUG. 30, 1919.

1,338,522.

Patented Apr. 27, 1920.

Inventor:
John P. Nicolle
By William Clinton
Attorney

UNITED STATES PATENT OFFICE.

JOHN P. NICOLLE, OF MONTREAL, QUEBEC, CANADA.

CLEAT FOR BARRELS.

1,338,522.

Specification of Letters Patent. Patented Apr. 27, 1920.

Application filed August 30, 1919. Serial No. 320,902.

To all whom it may concern:

Be it known that I, JOHN P. NICOLLE, a subject of the King of Great Britain, residing at Montreal, Province of Quebec, 5 Canada, have invented certain new and useful Improvements in Cleats for Barrels; and I do hereby declare that the following is a full, clear, and exact description of the invention, such as will enable others skilled 10 in the art to which it appertains to make and use the same.

This invention relates to cleats for barrels and the principal object is to relieve the barrel head from pressure that would tend 15 to bulge or swell the same.

Another object of the invention is to provide a binder adapted for holding the barrel staves in engagement with the head of the barrel and at the same time reinforcing 20 the barrel head.

A further object is to provide a cleat which is adaptable for use on barrels of various sizes.

With the above and other objects in view 25 which will hereinafter appear as the description continues, the invention consists of the novel features of construction, combination and formation of parts as will be hereinafter more fully described and particularly pointed out in the appended 30 claims.

In the accompanying drawings has been shown a simple and preferred form of the invention, it being, however, understood 35 that no limitation is necessarily made to the precise structural details herein exhibited, but the right is hereby reserved to any changes, alterations or modifications to which recourse may be had that come within 40 the scope of the claims without departing from the spirit of the invention or sacrificing the efficiency of the same.

In the drawings:—

Figure 1 is a perspective view illustrating 45 a barrel with the invention applied;

Fig. 2 is a top plan view of a cleat showing the same applied to a barrel, the latter being illustrated in top plan;

Fig. 3 is an enlarged plan view of the 50 cleat before its application to a barrel; and,

Fig. 4 is a vertical section parts being broken away illustrating the invention applied to a barrel.

In the drawings in which like numerals 55 of reference indicate like parts in all the figures, 1 designates the barrel which is pro-

vided with the usual head groove 2 in which the head 3 is fitted, the latter being usually held in place by nailing.

To provide for the quick attachment of 60 the heads in place in the barrel, in a firm and convenient manner, so that the head may not be removed or become loosened in transit, I provide a device which constitutes 65 my invention which consists of an oblong metallic strap 4 having its opposite end portions slit centrally at 5 to form the tongues 6. By this stamping operation a broad flat 70 central surface 7 is provided and likewise the end portion tongues 6 are provided with 75 angularly disposed scorings 8 and 9.

The cleat is first attached to the head 3 by 80 nails 10 passing through openings 11 in the flat central part 7 and then each tongue 6 is folded outwardly upon the scoring 8 and 75 in this position being thus disposed at an angle to each other and the part 7.

The tongues 6 are sufficiently flexible to 85 permit manipulation by lowering whereby the ends may be made adaptable for use on barrels of various configurations and sizes.

Each tongue member 6 has its ends provided with hook like portions 12 that snugly 90 fit over the ends 13 of the staves and the hoop 14, and project downwardly as at 15 85 to lie beneath the hoop 13, which is driven down over the head 3.

The extreme end portions of the tongues 6 at the base of the hooks 12 are provided 95 with openings 16 and 17, through which pass nails 18 for securing the tongue ends to the staves.

Having thus fully described my invention, what I claim as new and desire to secure by Letters Patent is:—

1. As a new article of manufacture, a head securing device, comprising a rectangular metallic strap member having its end portions slit to provide tongues, said tongues formed with a series of angularly 100 disposed scorings, each of said tongues at the end portions of said member, adapted to be bent outwardly on one of said scorings and the metal between the other of said scorings, adapted to form hooks for engaging 105 the upper end of the barrel staves and the hoop.

2. In combination with a barrel having a head and a hoop encircling the barrel adjacent to the head, of a head retaining device consisting of a metallic strap member having a flat central portion secured to the 110

outer face of the head, said strap member having its opposite end portions slit to form tongues, said tongues adapted to be folded diagonally over a portion of the flat central portion of said strap member and being disposed at an angle to each other, the outer ends of said tongues adapted to be bent over

the upper edges of the staves and hoop and downwardly for attachment to the barrel below said hoop.

10

In witness whereof I have hereunto set my hand.

JOHN P. NICOLLE.
